No. 36,830.

Patented March 1, 1904.

UNITED STATES PATENT OFFICE.

JAMES MADDOCK, OF ALSAGER, ENGLAND, ASSIGNOR TO MADDOCK & MILLER, A CORPORATION OF NEW YORK.

DESIGN FOR A DISH.

SPECIFICATION forming part of Design No. 36,830, dated March 1, 1904.

Application filed January 20, 1904. Serial No. 189,917. Term of patent 3½ years.

To all whom it may concern:

Be it known that I, JAMES MADDOCK, a citizen of Great Britain, and a resident of Alsager, in the county of Chester, England, have 5 invented a new, original, and ornamental Design for a Dish.

In the drawing there is illustrated a top plan view of a dish embodying my design.

What I claim is—

The ornamental design for a dish as shown. 10

JAMES MADDOCK
